CLAIM

The ornamental design for a display unit for sheet like materials, as shown and described.

DESCRIPTION

FIG. 1 is a perspective view of a display unit for sheet like materials showing our new design;

FIG. 2 is a front elevational view, the rear view being identical thereto;

FIG. 3 is a side elevational view, the opposite side being identical thereto;

FIG. 4 is a top plan view thereof; and

FIG. 5 is a sectional view looking down along line 5—5 of FIG. 2.
